[57] CLAIM

The ornamental design for an image scanner, as shown and described.

DESCRIPTION

FIG. 1 is a front view of the image scanner embodying my new design;

FIG. 2 is a rear view thereof;

FIG. 3 is a left side view thereof;

FIG. 4 is a right side view thereof;

FIG. 5 is a bottom side view thereof;

FIG. 6 is a top plan view thereof;

FIG. 7 is a perspective view as seen from the top and front of present FIG. 6;

FIG. 8 is a perspective view with the upper part of the support arm being pushed back into the lower part of the support arm as seen from the top and front; and,

FIG. 9 is a perspective view with all the parts being folded as seen from the top and front.
